UNITED STATES PATENT OFFICE.

GERRIT HILGERS, OF ROTTERDAM, NETHERLANDS.

LIFE-BOAT FOR SUBMARINE VESSELS.

1,081,740.

Specification of Letters Patent. Patented Dec. 16, 1913.

Application filed July 5, 1912. Serial No. 707,909.

To all whom it may concern:

Be it known that I, GERRIT HILGERS, a subject of the Queen of the Netherlands, residing at Bothastraat 23^B, Rotterdam, Kingdom of the Netherlands, have invented certain new and useful Improvements in Life-Boats for Submarine Vessels, of which the following is a specification.

The present invention relates to lifeboats which are housed in submarine vessels their upper edge forming a water-tight joint therewith. The lifeboat is completely covered in a water-tight manner by a deck and a hemispherical deck light is arranged there-in. By means of a manhole in the bottom of the boat the crew can reach it from the interior of the submarine. The fixing of the edge of the boat or of the boat itself to the submarine is effected in such a manner that it can readily be disconnected from the interior of the boat. Now if the manhole is closed and the attachment of the boat released, owing to its buoyancy it will rise to the surface of the water carrying with it the members of the crew. The life-boat is fixed by means of screws inserted in its upper edge and adapted to be loosened from the interior of the boat. The boat is also retained by means of cam shafts all of which are released simultaneously. In case the boat should not ascend by buoyancy alone after it has left its seat pressure screws are arranged in addition to the fixing screws. In order that the external water may flow beneath the lifeboat, a pipe provided with a cock is also arranged on the edge of the boat in such a manner that when the cock is opened communication is established between the external water and the space beneath the boat. The air is thus able to escape from this space and water to enter it. In order to prevent the water flowing beneath the lifeboat from entering the interior of the submarine itself, a partition is firmly built into the body of the submarine and surrounds the lifeboat leaving a very small interval. This wall is also provided with a manhole which registers with the manhole in the bottom of the boat. When this manhole is closed the external water is not able to enter the interior of the submarine vessel when this water is admitted beneath the lifeboat. Normally the lifeboat is firmly bolted to the submarine vessel; the cocks of the water admission pipe are closed and both manholes are open. In

case of need the crew passes through the two manholes up into the lifeboat; first of all the manhole in the partition is closed and then the manhole in the bottom of the lifeboat itself. The cocks on the water inlet pipes are then opened so that the external water is able to enter the space between the lifeboat and the partition and finally the connecting screws are released and the screw holes thus freed again closed by means of caps, whereupon the cam shafts are all simultaneously released. The boat is then able to rise freely. If, however, for any reason, such for example as the adhesion of its joint-forming edge, it should not rise, the boat can be detached from its seat forcibly by rotating the pressure screws.

An embodiment of the lifeboat for submarine vessels is illustrated in the accompanying drawing, in which:

Figure 1 is a side elevation of a submarine vessel provided with two lifeboats. Fig. 2 is a side elevation of the boat and a portion of the submarine in longitudinal section to a larger scale. Fig. 3 is a top view of the lifeboat with the deck partly removed, to a larger scale. Fig. 4 is a vertical cross section on the line I—II of Fig. 2 through the lifeboat fixed to the body of the submarine. Fig. 5 is a vertical section to a larger scale of the cam shaft arrangement fitted to the edge of the lifeboat firmly bolted to its seat. Fig. 6 is a similar section to Fig. 5 but through a fixing bolt.

In the deck 1 of the submarine 2 an opening is provided on the upper side which corresponds to the form of the edge of the boat. This opening is cut off in a water-tight manner from the interior of the vessel by a partition 3 built into the ship; this partition is of such a form that the life-boat can be inserted in the cavity formed by the partition. In the bottom of this partition a manhole 5 adapted to be closed by a rotatable hinged and water-tight cover 4 is arranged. In the longitudinal direction of this partition supports 6 are arranged for the reception of the boat inserted in the cavity. Around the upper edge of the cavity formed by the partition an inwardly projecting flange 7 is provided and is connected with the partition in the form of a T-piece 8. The projecting upper edge 9 of the boat rests on this flange 7 to which it is fixed by means of a special device from the interior of the boat. The lifeboat itself is formed

in such a manner that the wall 10 rests on the supports 6 when the boat is in position while the projecting edge 9 rests on the flange 7. In order to simplify the construction the flange 7 may constitute a plane surface but other forms of flange may also be selected.

In the bottom of the lifeboat opposite the manhole 5 in the partition a manhole 11 is provided, and, like the manhole 5, must be adapted to be closed from the interior of the lifeboat. By means of the cover 12 the manhole 11 is closed watertight. The entirely closed deck of the boat is provided with a hemispherical deck light known *per se* which is normally closed water-tight but which can be opened when the boat is floating on the surface of the water. The projecting edge 9 of the boat can be formed as follows (Fig. 6): The angle pieces 13 and 14 which are rigidly connected one with the other are fixed on the one hand to the wall of the boat 10 and on the other hand to the part 15 of the boat which is itself connected with the deck 16 of the boat. The method of connecting the edge 9 of the boat or boat itself with the flange 7 or with the submarine may be as follows: (Fig. 6): the bolts 17, preferably of copper or brass, are firmly screwed into the flange 7 or into a beading 18 fixed thereon. Through the lower rim of the edge 9 or through the two angle pieces 13 and 14 which are rigidly connected one with the other, bushes 19, preferably of copper or brass, are firmly inserted. When the boat is in place the bolts 17 pass through the bushes 19 while the angle piece 13 rests on a strip of indiarubber 20. In the interior of the projecting edge 9 sufficient space is left for screwing copper or brass nuts 21 onto the upper end of the bolt 17 and tightening them up. This will cause the boat to rest on the supports 6 (Fig. 4) and it is connected in a water-tight manner with the submarine while the deck 16 and its projecting edge 22 entirely covers the cavity formed by the partition.

Over the upper threaded portion of the bushes 19 caps 24 provided with a hexagonal head 23 are screwed and rest on rings 25 of packing material. Between the bolts 17 a suitable number of pressure screws 26 are arranged (Fig. 3). Pipes 28 provided with cocks 27 conduct the external water into the space 29 located beneath the flange 7 and between the partition and the wall of the boat, when the boat is to be released.

In addition to being fixed by the means described above the lifeboat is connected with the flange 7 by a number of (say eight) cam shafts in the following manner (Fig. 5); between two fixing bolts 17 flanges 30 are connected with the inner edge of the wall of the boat 10 in such a manner that the end of the cam shaft 32, which is car-

ried in a water-tight manner through this flange and provided with a cam 31, engages beneath the flange 7 in its raised position. The collar 33 prevents the cam shafts from being pressed forward too far as it strikes against the front edge of the flange 7. On its inner side the cam shaft 32 is bent at a right angle so that it can be rotated by means of this bent portion 34. In the horizontal position these bent portions 34 engage in slots 35 in the arms 37 rigidly connected with the two horizontal shafts 36 arranged in the direction of the length of the boat. By simultaneously acting upon the two levers 38 which are also rigidly connected with the shafts 36, all the cam shafts on the boat are drawn back into the recesses 39 simultaneously.

The rudder 40 (Fig. 2) of the boat can be rotated entirely beneath it so that but little space is occupied.

The boat is used in the following manner: The crew pass through the manholes 5 and 11 into the boat then first of all close the cover 4 of the manhole 5 and then the cover 12 of the manhole 11 in the bottom of the boat itself; the cocks 27 are then opened so that the space 29 is placed in communication with the external water, whereupon the caps 24 and nuts 21 are unscrewed and the caps 24 are again screwed on. The boat is then still retained by the cam shafts 32 (Fig. 5). These members are rotated through 90° so that the cams 31 no longer contact with the flange 7 and simultaneously the bent portions 34 of the cam shafts 32 engage in the slots 35 in the arms 37. The boat can then separate slightly from its seat; it cannot, however, be expected that the boat should become actually detached from its seat as this is prevented by the adhesion of the indiarubber strip 20 and the air which has not yet entirely escaped from the space 29. The pressure screws 26 are then rotated so that the boat is raised forcibly (Fig. 3). The boat is then retained by the cam shafts 32 only so that when they are all simultaneously withdrawn by acting upon the two levers 38 the boat is released and rises.

It is advisable to provide all the parts to be released in the boat with a hexagonal head of the same size. The cam shafts 32 can also be provided with a hexagon (Fig. 5) so that they can all be turned by a spanner of the same size. An adequate number of these spanners should always be contained in the boat ready for use. A small electric battery with lamps connected therewith should also be kept in the boat. The boat can also be provided with a hand-operated screw propeller and other means for driving the boat when it floats on the surface of the water.

The simple construction and ease of manipulation of the boat render it possible to

detach it in about twenty minutes; a practiced crew could easily perform the operation in far less time. The known means for replacing the vitiated air in the boat can also be used. The weight of a life boat five meters long, two meters wide and 1.8 meters high can be taken as approximately from 5 2,000 to 3,000 kgs. with a light construction, while the quantity of water displaced is 10 about 8,000 liters so that the total buoyancy is 8,000 kgs. With a load of 2,400 kgs. corresponding approximately to the weight of three men there is always an excess buoyancy of 2,600 to 3,600 kgs.

15 The boat can be housed on any part of the deck of the submarine, an appropriate position being above the forecastle where the crew is berthed while if necessary a second boat can be housed in the after deck.

20 What I claim and desire to secure by Letters Patent of the United States is:—

1. In combination a submarine vessel, a lifeboat located in a compartment in same, screw-threaded members mounted on the 25 walls of said compartment and projecting into said lifeboat members operable from within said lifeboat and co-acting with said screw threaded members, cam members simultaneously operable from within the 30 lifeboat and engaging members on the walls of said compartment and constituting the means of effecting the complete release of the lifeboat from the said compartment.

2. In combination a submarine vessel, a 35 lifeboat located in a compartment therein, screw threaded members mounted on the walls of said compartment and projecting into said lifeboat members operable from within the lifeboat and co-acting with said screw threaded members for partially retaining the lifeboat in said compartment, cam shaped members coupled together so that they may be simultaneously operated from within the lifeboat, and engaging members on the walls of said compartment.

40 3. In combination a submarine vessel, a lifeboat located in a compartment therein, screw-threaded members mounted on the walls of said compartment and projecting

45 into the lifeboat members co-acting with 50 said screw threaded members and operable from within the lifeboat, screw threaded caps adapted to render the connection between said members watertight, pressure screws operable from within the lifeboat and 55 adapted to assist the release of same from said compartment, cam shaped members co-operating with members on the walls of said compartment and coupled together so that they may be simultaneously operated 60 from within the lifeboat, a manhole door in said lifeboat, a corresponding manhole in the submarine shell and a conduit for establishing communication between the outer water and the interior of said compartment. 65

4. In combination a submarine vessel; a lifeboat located in a compartment therein, screw threaded members mounted on the walls of said compartment and projecting into the lifeboat, members co-acting with 70 said screw threaded members and operable from within the lifeboat, screw threaded caps adapted to render the connection between said members watertight, pressure screws operable from within the lifeboat and 75 adapted to assist the release of same from said compartment, cam-shaped members co-operating with members on the walls of said compartment and coupled together so that they may be simultaneously operated 80 from within the lifeboat, a manhole door in said lifeboat, a corresponding manhole in the submarine shell, a conduit for establishing communication between the outer water and the interior of said compartment, a 85 cover on said lifeboat which insulates the interior of said compartment from the outer water, and a hemispherical deck light on said cover adapted to be opened when said lifeboat is floating at the surface of the 90 water.

In testimony whereof I affix my signature in presence of two witnesses.

GERRIT HILGERS.
